James M. Long, South Hadley, Mass., assignor to A. G. Spalding & Bros. Inc., Chicopee, Mass., a corporation of Delaware

Filed Jan. 11, 1967, Ser. No. 5,381

Term of patent 3½ years

(Cl. D34—5)

Fig. 1

Fig. 2

FIG. 2 is an end view of FIG. 1; and

FIG. 3 is a back view taken in the direction 3—3 of FIG. 2.

The characteristic feature of my design resides in the particular configuration of the rear of the club head as shown.

The dash lines in FIG. 1 show conventional face scoring and are for illustrative purposes only.

I claim:

The ornamental design for a golf club head, as shown and described.
